Application December 16, 1952, Serial No. 22,724

Term of patent 7 years

(Cl. D72—1)

To all whom it may concern:

Be it known that I, Lloyd W. Rittenhouse, a citizen of the United States of America, residing at Honeoye Falls, in the county of Monroe and State of New York, have invented a new, original, and ornamental Design for a Door Chime Housing, of which the following is a specification, reference being had to the accompanying drawing, forming a part thereof.

In the drawing:

Fig. 1 is a view in front elevation of a door chime housing showing my new design;

Fig. 2 is a side elevation, and

Fig. 3 is a top plan view.

The drawing is lined to indicate contrasting colors.

I claim:

The ornamental design for a door chime housing, as shown and described.

LLOYD W. RITTENHOUSE.
